ALFRED C. NELSON, OF LAKEWOOD, OHIO.

FURNACE-CHARGING MECHANISM.

1,177,720.

Specification of Letters Patent.

Patented Apr. 4, 1916.

Application filed September 17, 1915. Serial No. 51,198.

To all whom it may concern:

Be it known that I, ALFRED C. NELSON, a citizen of the United States, residing at Lakewood, in the county of Cuyahoga and State of Ohio, have invented certain new and useful Improvements in Furnace-Charging Mechanisms, of which the following is a specification.

This invention relates to mechanism controlling the distribution of material in blast furnaces or other combustion furnaces, into which materials such as fuel, ore, and fluxes are charged through an opening at the top of the furnace.

15 It is particularly applicable to furnaces equipped with the "bell and hopper" charging top, well known in the blast furnace art.

In the charging of furnaces of the character mentioned it is common practice to hoist the materials to the top by means of skips the contents of which are automatically dumped into a receiving hopper, subsequently discharged from the receiving hopper into a main hopper which is capable of holding several skip loads, and finally the material is discharged from the main hopper into the furnace. The materials, such as coal, coke, ore, limestone, etc., which are thus placed in the furnaces, being granular and of different grades of coarseness, or, made up of what is known in the art as "lumps and fines," arrange themselves in the furnace in accordance with the positions they have occupied in the main hopper previous to being discharged into the furnace. It has been found that the most satisfactory results are obtained when most of the "lumps" lie in the center of the furnace and most of the "fines" lie next to the walls. It has been found further that if the draft through the furnace is obstructed, on account of the uneven distribution of coarse and fine materials, so as to be deflected against the walls of the furnace at one point more than another, the furnace lining at the attacked point is burned away sooner than at other points. This results in poor economy of operation and necessitates frequent relining of the furnace. When the draft passes uniformly straight through the furnace and is not deflected against the walls at one point more than another the burning away or erosion of the walls is uniform over their entire surfaces,

operation is the most efficient and repairs are minimum.

The principal object of my invention is to provide new and improved means for effecting and controlling the distribution 60 of the charging materials in the main hopper and thus, in large measure, to control their distribution in the furnace.

In the accompanying drawings Figure 1 is a vertical, axial section through a blast 65 furnace top equipped with my invention in which the distributor is closed; Fig. 2 is a part section, part side view at right angles to Fig. 1; Fig. 3 is a view similar to Fig. 1, except that in Fig. 3 the distributor is 70 opened to allow the materials to enter the main hopper. Figs. 4 and 5 are respectively an end view and a longitudinal section of the distributor revolving ratchet, Fig. 4 being a section on line *a*—*a* of Fig. 5; Figs. 75 6 and 7 are respectively a plan and elevation of a distributor having three blades; Fig. 8 shows a modified form of distributor revolving element. Fig. 9 is a detail vertical section illustrating the manner of supporting 80 the tubular shaft 14.

In the drawings 1 represents the top of the furnace wall, 2 the bell, 3 the main hopper and 4 the skip. The mechanism for raising and lowering the skip is not shown 85 but it will be understood that this may be of any suitable construction or that other means may be employed for bringing materials to the top of the furnace and discharging them into the receiving hopper.

90 The main hopper of the furnace has the shape of an inverted frusto-conical shell set in a suitable opening of the top of the furnace, 1. A flange, 5, formed on the hopper supports it with a suitable gas tight joint upon the top plate, 6, of the furnace. Covering the hopper and forming a support for the distributing device is the frusto-conical shell, 7, provided with a flange, 8, at its base, making a gas tight joint with the upper side of the flange, 5, of the main hopper.

To the top of the cover, 7, is secured the circular flanged fitting, 9, upon which rests and is secured the cylinder, or chute, 10. Secured to the top of the cylinder, 10, is 105 the receiving hopper, 11, shown in the drawings as being adapted to accommodate a double skip hoisting device. The hopper, 11, may, however, be of any convenient or desirable size or shape.

The main bell, 2, is supported by the rod, 12, which, at 3, is secured to any convenient operating mechanism well known in the art. Surrounding the rod, 12, is the tube, 14, having secured to it at its lower end the upper bell, 15, and the distributor blades, 16. The blades are preferably helicoidal in form but this shape may not be strictly adhered to. I have found, however, the helicoidal blades 10 to be satisfactory for the purposes of my invention. Tube 14, with the bell, 15, and blades, 16, is rotatable and slidable upon rod 12. Tube, 14, is supported at the top by a ball bearing, 17, the tube being provided 15 with an external flange which rests on the top of the upper ball race, while the lower ball race is supported by the bracket, 18. Bracket, 18 is in turn supported by the links, 19, attached to lever, 20, which is of usual 20 construction, fulcrumed at 21 to the super structure, 22, of the furnace. It will be understood that lever 20 is actuated by any of the usual power devices employed for this purpose, and that its function is to raise and 25 lower the upper bell 15 together with the distributor blades 16 and tube 14.

Fixed to the tube, 14, adjacent to the ball bearings, 17, is the bevel gear, 23, operatively engaged with the bevel pinion, 24, 30 which is mounted upon and has a driving connection with shaft, 25, which has bearings in the bracket, 18.

Rotatably mounted upon shaft 25 but secured against longitudinal displacement is 35 the pinion, 26, whose teeth engage with the teeth of rack, 27, which is secured to the side wall of the hopper, 11. Gear, 26, is provided with a cylindrical recess, 28, having internal ratchet teeth, 29. The collar, 30, having a driving connection or formed integrally with shaft, 25, carries the pawls, 31, which are adapted to engage the ratchet teeth, 29, of gear, 26. Lugs, 32, formed upon the collar, 30, are abutments for the 45 springs, 33, which force the pawls, 31, into engagement with the ratchet teeth, 29.

The ratchet mechanism above described, as shown in the drawings, is arranged so that when the tube 14, bell 15, and blades 16, 50 constituting the distributor revolving element are being lowered by the downward movement of lever 20 and bracket 18, the shaft 25 will be forced to rotate, thereby rotating the revolving element. When, by the upward movement of bracket 18 and lever 20, the distributor element is raised, the pinion 26 engaging rack 27 will be made to rotate in the direction in which the pawls 31 do not engage the ratchet teeth 29, and consequently the shaft 25 will remain stationary 55 and the distributor revolving element will not be rotated.

The ratchet mechanism may be arranged to cause the distributor revolving element to rotate either when being lowered or when

being raised. If arranged to cause rotation on the downward stroke, the ratchet will slip on the upward stroke and the revolving element will not rotate. If arranged to cause the revolving element to rotate on the upward stroke, it will not be caused to rotate on the downward stroke. It will be seen that by varying the diameters of the gears, 23, 24 and 26, and by varying the distance through which the distributor is raised and lowered by the lever, 20, the angle through which the distributor is rotated during its vertical movement may be predetermined. To permit the distributor blades, 16, to readily enter the cylinder, 10, I prefer to 70 slightly taper the latter, making the larger end at the bottom as shown in the drawings. Pinion, 26, is held in engagement with rack, 27, by means of the projection, 34, formed upon the bracket, 18, and extending behind 75 the rack bar as shown in Fig. 5. Secured to the outer end of pinion, 26, is the dust plate, 35, which serves also to retain grease or other lubricant within the recess, 28, thus insuring the proper operation of the ratchet 80 mechanism.

In the drawings the rack, 27, is shown in Fig. 5 to be located on the right of pinion 26, which will cause rotation of the revolving element on its downward stroke. By 95 providing holes 36, in the wall of the hopper, 11, the rack may be located on the left of the pinion, 26, as viewed in Fig. 5 and thereby cause the revolving element to rotate on its upward stroke. As the materials pass the blades, 16, of the distributor they 100 tend to cause the revolving element to rotate. As shown in the drawings the pawls, 31 resist this rotation and, on the downward stroke, cause the element to rotate against 105 the rotative force of the materials exerted on the blades. It is evident that by reversing the teeth, 29, of the ratchet and by reversing the pawls, 31 to correspond, the distributor revolving element may be made to 110 revolve in the opposite direction from that caused by the arrangement of parts shown 113 in the drawing.

In Figs. 6 and 7 I have shown a distributor provided with three blades. In all of the 115 distributors shown in the drawings the blades extend 180 degrees around the tube to which they are secured. Any desired number of blades may be used in the distributor and they may encircle the tube to any extent 120 found necessary or desirable. As the material passes down through the cylinder, 10, it will be divided into as many paths as there are distributor blades and will be deposited at the same number of points in the main 125 hopper below. By rotating the distributor through the proper angle the material passed through it upon successive lowerings of the bell, 15, may be deposited between the points where the material was deposited previously. 130

By observation the amount of rotation necessary to cause the material to be deposited in the main hopper in the best possible way may be determined, the rotating mechanism 5 adjusted accordingly, and thereafter the correct distribution of materials will automatically upon the operation of the charging mechanism.

In Fig. 8, I have shown a modified form 10 of distributor revolving element in which the blades, 37, do not extend below the top of the bell, 38. In some instances this construction may be found desirable or convenient, such, for instance, as in the case of 15 changing an old furnace charging mechanism so as to embody my invention but utilize the bell and tube of the old structure.

I am aware that other forms of distributors for similar purposes have been previously proposed, but in all those with which 20 I am familiar the entire charge of material from the receiving hopper is discharged in a single direction into the main hopper, or, no attempt is made to direct the material as 25 it enters the main hopper except as it may be deflected by the upper bell without other distributing means. By dividing the material flowing from the receiving hopper into the main hopper into a plurality of streams 30 or paths which fall or are deposited at different points in the main hopper, I am able to better equalize and control the distribution of material in the main hopper, and, as previously pointed out, as the distribution 35 of materials in the furnace depends almost entirely upon the distribution of materials in the main hopper, I am enabled by my invention to better distribute and control the distribution of materials in the furnace.

40 While the usual mode of operating distributors is to hold the upper bell closed while the material is being discharged from the skip into the receiving hopper, it is possible with my distributor to lower the bell 45 and the distributor blades as shown in Figs. 1 and 3 before starting to discharge the contents of the skip, 4, into the hopper, 11, and thereafter when the material is being discharged from the skip it will fall directly 50 through the receiving hopper, 11, and cylinder, 10, upon the blades, 16, of the distributor and be distributed through in the main hopper, 3, in much the same manner as it is distributed after being first collected in 55 the hopper, 11, and later discharged into the main hopper, 3.

Various modifications of my invention may be made without departing from its scope.

60 I claim:-

1. In a furnace charging mechanism, a main hopper adapted to discharge into the furnace, a bell closing the bottom of this hopper, a receiving hopper having a chute emptying into said main hopper, a bell 65

adapted to close the discharge end of this chute, and a plurality of deflectors immediately above the bell and at the discharge end of said chute to divide the discharging material into a plurality of streams as it enters 70 the main hopper.

2. In a furnace charging mechanism, a main hopper adapted to discharge into the furnace, a bell closing the bottom of this hopper, a receiving hopper having a chute emptying into said main hopper, a bell 75 adapted to close the discharge end of this chute, a plurality of deflectors immediately above the bell and at the discharge end of said chute to divide the discharging material into a plurality of streams as it enters 80 the main hopper, and means for rotating the deflectors to vary their points of discharge.

3. In a furnace charging mechanism, a main hopper adapted to discharge into the furnace, a bell closing the bottom of this hopper, a receiving hopper having a chute emptying into said main hopper, a bell 85 adapted to close the discharge end of this chute, a plurality of deflectors at the discharge end of said chute to divide the discharging material into a plurality of streams as it enters 90 the main hopper, and means for raising and lowering the deflectors relatively to the outlet of said chute.

4. In a furnace charging mechanism, a main hopper adapted to discharge into the furnace, a bell closing the bottom of this hopper, a receiving hopper having a chute emptying into said main hopper, a bell 95 adapted to close the discharge end of this chute, a plurality of deflectors at the discharge end of said chute to divide the discharging material into a plurality of streams as it enters 100 the main hopper, means for raising and lowering the deflectors relatively to the outlet of said chute, and means for rotating said deflectors to vary their points of discharge simultaneously with the operation of said raising and lowering means.

5. In a furnace charging mechanism, a distributor for the materials of the charge consisting of a cylindrical chute having an outlet through which the materials pass when entering the furnace, and a plurality of inclined deflectors supported upon a shaft, said shaft being concentric with the chute, and said deflectors being arranged in the same horizontal plate and at equidistant points around said shaft to cause the materials to be divided into a plurality of paths.

6. In a furnace charging mechanism a distributor consisting of a chute, having an inlet and an outlet, means for closing and opening the outlet of said chute, and a plurality of inclined deflectors supported in said chute at equidistant points around the same and at the discharge end thereof, so as to cause the materials discharged from 120 125 130

- said chute to be divided into a plurality of paths.
7. In a furnace charging mechanism the combination of a main hopper and means for closing and opening its lower end, a material receiving hopper located above the main hopper, a chute forming an outlet for the passage of material from the material receiving hopper to the main hopper, and a plurality of approximately helicoidal deflectors located in the path of the material where it leaves the chute, adapted to cause the materials discharged from said chute to be divided into a plurality of paths.
- 15 8. In a blast furnace charging mechanism the combination with a main hopper and means for closing and opening its outlet into the furnace, of a receiving hopper located above the main hopper, a cylindrical chute connecting the receiving hopper with the main hopper, a plurality of deflectors supported by a shaft in said chute, said deflectors being arranged to divide the materials passing through said chute into a plurality of paths to cause them to be distributed to a plurality of points in the main hopper, and means for rotating said shaft and said deflectors in said chute.
9. In a blast furnace charging mechanism the combination with a main hopper and means for closing and opening its outlet into the furnace, of a receiving hopper located above the main hopper, a chute connecting the receiving hopper with the main hopper, a plurality of deflectors in said chute arranged to divide the materials passing through said chute into a plurality of paths to cause them to be distributed to a plurality of points in the main hopper, and a single means for closing and opening the outlet of said chute into the main hopper and for raising and lowering said deflectors in said chute.
10. In a blast furnace charging mechanism the combination with the receiving hopper, the plurality of deflectors and tubular shaft therefor, said tubular shaft being supported at its upper end by a swivel bearing in a bracket connected to raising and lowering means, of a gear fixed to said tubular shaft, a second shaft rotatively mounted in bearings in said bracket, a gear fixed to said second shaft and engaging the gear fixed to said tubular shaft, a third gear rotatively mounted upon said second shaft and in engagement with a rack fixed to the wall of the receiving hopper, and means coöperating with said second shaft and said third gear to cause the rotation of said third shaft when said third gear is rotated in one direction, whereby the said tubular shaft and deflectors are caused to rotate in unison with a vertical movement of said bracket.
- 15 11. In a furnace charging mechanism a distributor for the materials of the charge consisting of a chute through which the materials pass when entering the furnace, a bell for closing the outlet of said chute, said bell being fixed to a shaft concentric with said chute, and a helicoidal blade also fixed to said shaft above said bell, and having its axis of generation in alinement with the axis of said bell.
12. In a charging mechanism a distributor for the materials of the charge consisting of a chute through which the materials pass, a shaft in said chute concentric therewith, and a helicoidal blade fixed to said shaft, and having its axis of generation in alinement with the axis of said shaft.
13. In a furnace charging mechanism, a main hopper adapted to discharge into the furnace, a bell closing the bottom of this hopper, a receiving hopper having a chute emptying into said main hopper, a bell adapted to close the discharge end of this chute, a plurality of approximately helicoidal deflectors at the discharge end of said chute to divide the discharging material into a plurality of streams as it enters the main hopper, and means for raising and lowering the deflectors relatively to the outlet of said chute.
14. In a furnace charging mechanism, a main hopper adapted to discharge into the furnace, a bell closing the bottom of this hopper, a receiving hopper having a chute emptying into said main hopper, a bell adapted to close the discharge end of this chute, a plurality of approximately helicoidal deflectors at the discharge end of said chute to divide the discharging material into a plurality of streams as it enters the main hopper, means for raising and lowering the deflectors relatively to the outlet of said chute, and means for rotating said deflectors to vary their points of discharge simultaneously with the operation of said raising and lowering means.
